UNITED STATES PATENT OFFICE.

JOHN PETZ, OF DETROIT, MICHIGAN, ASSIGNOR OF ONE-HALF TO JOHN PHILLIPS, OF SAME PLACE.

SHOW-CASE.

SPECIFICATION forming part of Letters Patent No. 634,701, dated October 10, 1899.

Application filed April 12, 1899. Serial No. 712,773. (No model.)

To all whom it may concern:

Be it known that I, JOHN PETZ, a citizen of the United States, residing at Detroit, in the county of Wayne and State of Michigan, have 5 invented certain new and useful Improvements in Show-Cases, of which the following is a specification, reference being had therein to the accompanying drawings.

My invention relates to show-cases of that 10 class which are provided with transparent front and top and such as are usually employed in stores for the display of goods.

It is the object of my invention to provide 15 means for brilliantly illuminating the interior of the case without permitting the direct rays from the light used for that purpose to pass out through the transparent front and top, thereby preventing the annoyance to both customer and salesman produced by the 20 blinding glare of the light when it is exposed to direct view.

To this end the invention consists in the 25 peculiar construction of a show-case having a frame-rail provided with a depending flange or shield and a lamp or other illuminant arranged to have a portion of its direct rays cut off by said shield, and thereby prevented from 30 passing out through the transparent plates.

The invention further consists in the 35 construction, combination, and arrangement of the various parts, as more fully hereinafter described and claimed.

In the drawings, Figure 1 is a sectional perspective view of my case. Fig. 2 is a cross-section through the case, showing a slightly-modified construction. Fig. 3 is an enlarged section through the frame-rail of the case, also slightly modified; and Fig. 4 is a longitudinal section on line xx , Fig. 3.

40 A is a show-case of usual construction, except as hereinafter described, comprising the glass or transparent front plate a and top plate b . These plates are preferably secured in place by being seated at their edges in top 45 and bottom rails constituting the framework of the case. The front top rail B of this frame is recessed on its inner edge, forming a groove or channel in which lamps for illuminating the case may be placed. I preferably form 50 this recess or channel, as shown in Fig. 3 of the drawings, by channeling out the frame-

rail, so as to leave the downwardly-projecting flange c on its inner side, which forms the shield for preventing the rays from the light passing out through the top plate of the case. 55 The shield for the front plate is preferably formed by a separate strip d , secured to the rail, and this strip may also form the securing means for holding said front plate to its rail.

The lights which I preferably employ for 60 illuminating the case are incandescent electric lamps, which are preferably of a cylindrical shape, so as to fit within the groove. The sockets for these lamps may be secured in any suitable manner to the rail, and the 65 wires extend preferably in channels e , formed along the upper face of the groove in the rail.

In order to prevent the heating effect of the lamps upon the case, I preferably arrange 70 a heat-shield C , which is formed of a strip extending longitudinally along the upper face of the groove in the rail and provided with ribs f , which hold it separated slightly from the rail, and thus form air-spaces between, which greatly assist in forming a heat-insulator. 75

In Fig. 2 of the drawings I show a modification in which the shields for the lamp instead of being formed integral with the rail consist of the plates g and h , secured to the 80 rail and surrounding the lamps sufficiently to prevent any direct ray therefrom passing out through either top or front of the case.

What I claim as my invention is—

1. In a show-case, the combination with 85 transparent top and front plates, of a frame-rail to which said plates are secured, a lamp secured to said rail within the case and a depending flange on said rail adapted to shield the direct rays of said lamp from passing out 90 from the case.

2. In a show-case, the combination with 95 transparent top and front plates, of a frame-rail to which the adjacent edges of said plates are secured having a recess formed therein, and an electric lamp or other illuminant placed in said recess for the purpose described.

3. In a show-case, the combination with 100 transparent top and front plates of a frame-rail to which the adjacent edges of said plates are secured, the inner portions of said rail

being formed with a longitudinal groove or channel, and a series of electric lamps or other illuminants placed in said groove for the purpose described.

5. In a show-case, the combination with transparent top and front plates, of a frame-rail to which the adjacent edges of said plates are secured, having a longitudinal groove or channel formed in its inner portion, a series of electric lamps secured in said groove and a lining for said channel forming a heat-shield.

5. In a show-case, the combination with transparent top and front plates, of a frame-

rail to which the adjacent edges of said plates are secured having a longitudinal groove or channel formed in its inner portion, a lining-strip secured within said groove separated from the walls thereof to form an air-space and a series of electric lamps secured within said groove for the purpose described.

In testimony whereof I affix my signature in presence of two witnesses.

JOHN PETZ.
